CLAIM

The new and ornamental design for a cable modem, as shown and described.

DESCRIPTION

FIG. 1 is a perspective view, showing our new design for a cable modem;
 FIG. 2 is a front elevation view thereof;
 FIG. 3 is a rear elevation view thereof;
 FIG. 4 is a right elevation view thereof (the left elevation view thereof being symmetrical thereto);
 FIG. 5 is a top plan view thereof; and,
 FIG. 6 is a bottom plan view thereof.
